TRUCK CRANE FOR FIFTH WHEEL

Lynn M. Francis, Detroit, Mich.

Application July 11, 1947, Serial No. 760,815

2 Claims. (Cl. 254—139.1)

1

The present invention relates to improvements in a detachable crane which is particularly adapted for mounting on the conventional fifth wheel of a tractor.

There are many instances when an operator of a fleet of trucks, for example, temporarily needs a mobile or portable crane for lifting heavy objects and for assisting in the loading of equipment. Prior to the present invention, cranes for such purposes were mounted on a truck or tractor for hauling to the work site as desired. A serious objection to such a practice has been the indefinite tying up of a tractor during periods when the crane is not in use. It is frequent that the crane is required only for part time use, so that a conveniently applied means for detachable mounting the crane to the tractor is highly desirable for freeing the latter for other purposes.

Accordingly, a primary object of the present invention is to provide a readily demountable crane mechanism which may be used for hoisting or lifting heavy objects and which may be quickly and easily detachably mounted on the conventional fifth wheel of a tractor, the crane being readily demountable after serving its temporary purpose so as to permit use of the tractor for other work.

Other objects of this invention will appear in the following description and appended claims, reference being had to the accompanying drawings forming a part of this specification wherein like reference characters designate corresponding parts in the several views.

In the drawings:

Fig. 1 is a side elevation of a demountable crane embodying the present invention and shown in position on the fifth wheel of a tractor.

Fig. 2 is essentially an enlarged end view taken from the left end of Fig. 1, the tractor being removed and a portion of the tractor chassis being shown in phantom.

Fig. 3 is essentially a side view of the crane apparatus shown in Fig. 2, the fifth wheel and portions of the tractor being shown in phantom.

Fig. 4 is an enlarged fragmentary section showing the attachment of the king pin to the crane support and being taken in the direction of the arrows essentially along the line 4—4 of Fig. 3.

Fig. 5 is an enlarged fragmentary section through the mechanism for clamping the crane support to the tractor frame and being taken in the direction of the arrows essentially along the line 5—5 of Fig. 3.

Fig. 6 is essentially a fragmentary top view of the cable winding winch.

Before explaining the present invention in detail, it is to be understood that the invention is not limited in its application to the details of construction and arrangement of parts illustrated in the accompanying drawings, since the invention is capable of other embodiments and of being practiced or carried out in various ways.

2

Also it is to be understood that the phraseology or terminology employed herein is for the purpose of description and not of limitation.

Referring to the drawings, a particular embodiment of a detachable crane employing the present invention is shown by way of example in Fig. 1 mounted on the conventional fifth wheel 10 of a tractor 11. Details of the crane construction are shown in the enlarged views, Figs. 2 and 3, wherein an angle iron truss structure provides the framework of the crane. A pair of heavy load supporting vertical uprights 12 are adjustably connected to the extensible stand or legs 13 by means of the bolts 14. A cross brace 15 or footing 15 secured to the base of the stand or legs 13 is provided for resting on the horizontal tractor channel frame structure 16, shown in phantom, Figs. 2 and 3. A horizontal winch supporting platform 17 is secured to the uprights 12 and legs 13 by a pair of the bolts 14, extends toward the tractor 11 over the fifth wheel 10 thereof, and provides the depending king pin 18 for locking within the open jaws of the fifth wheel according to conventional practice.

Inasmuch as the height of the fifth wheel 10 above the horizontal tractor frame 16 varies with different makes of tractors, a plurality of bolt holes 19 in the uprights 12 and legs 13 for the bolts 14 permit selective vertical adjustment of the footing 15 and enable the winch platform 17 to ride essentially horizontally with the footing 15 resting on the frame 16. A clamping assembly is provided at each end of the footing 15 for clamping the same to the channel frame 16 and includes a clamp 20 on the underside of the footing 15 for engaging a portion of the channel frame 16 between itself and the footing 15, a clamping bolt 21 extended upward through the clamp 20 and through a slotted bolt opening 22 provided therefor in the footing 15, and a handle nut 23 screwed on the clamping bolt 21 above the footing 15 for securely clamping the channel frame 16 between the footing 15 and clamp 20. The bolt slot 22 extends longitudinally of the footing 15 to permit lateral adjustment of the clamping assembly in accordance with the varying spacing between the horizontal channel frame members 16 of different types of tractors 11.

A pair of converging inclined crane booms 24 extend upward and rearward from opposite sides of the forward portion of the winch platform 17 to which they are secured by the bolts 25, to attachments near their mid-portions with the load supporting uprights 12 by means of the bolts 26. The upper ends of the converging booms 24 are joined by the pulley shaft 27 on which is journaled the pulley 28.

A pair of upper boom supports 29 extend from attachments at the ends of the pulley shaft 27 to attachments with the upper portions of the up-

rights 12 by the heavy shaft bolt 30. Similarly a pair of lower boom supports 31 extend from opposite ends of the shaft bolt 30 to the platform 17 whereat the bolts 25 secure both the booms 24 and supports 31 to the forward sides of the platform 17. The bolt 30 extends between the upper portions of the uprights 12 to secure one of each to the ends of the corresponding boom supports 29 and 31.

Figs. 3 and 6 show details of the winch construction, which comprises a hand operated winch in the present instance, although a motor-driven winch is feasible for use where desired with other embodiments of the present invention. The winch drum 33 is rotatable on the winch shaft 34, which is journaled at opposite ends within the pair of upright brackets 35, which in turn are secured to the winch supporting platform 17 by the plurality of bolts 36. Rotatable with the winch drum 33 is the large driven gear 37, which is in gear driving relationship with the small drive gear 38 mounted on the shaft 39 for rotation therewith. The shaft 39 is also journaled within the pair of upright brackets 35 and provides the crank arm 40 for rotation of the winch drum 33. A cable 41 is wound on the winch drum 33 and threaded through the pulley 28 and hoist pulley block 42 in a conventional manner for raising or lowering the hoist block 42 and load supporting hook 43 secured thereto upon rotation of the crank arm 40. A loop 44 to receive the hook 43 and to prevent swinging thereof when it is not in use is provided by the plate 45, secured to the rear portions of the uprights 12, Fig. 3. Unreeling of the winch drum 33 may be prevented by the pawl 46 pivotally secured at 47 to a projection of the platform 17 for engaging the teeth of the gear 37.

Details of the mounting of the king pin 18 to the platform 17 are shown in Fig. 4. The king pin 18 provides the flanged base 48 which rests on the upper surface of the platform 17 and holds the body of the king pin 18 in place as the latter projects through the opening 49 provided therefor in the platform 17. The flange 48 is detachably secured to the platform 17 by the plurality of bolts 50. Thus king pins of various sizes may be readily detachably secured to the platform 17.

In operation of the present invention, the crane assembly is mounted in position over the conventional tractor fifth wheel 10, with the king pin 18 locked within the jaw thereof by the conventional fifth wheel lock, and with the extensible legs 13 suitably adjusted so that the footing 15 rests on the frame 16 with the platform 17 essentially horizontal. The clamps 20 are then laterally adjusted to engage the horizontal channel frames 16 of the body of the truck 11 and are tightened by turning the respective handle nuts 23 to securely clamp the frames 16 to the footing 15. The crane is readily dismounted upon loosening the handle nuts 23 and unlocking the king pin 18 from the fifth wheel 10.

By means of the drawings and description herein, a novel and desirable crane and mounting have been disclosed which is particularly adapted for detachably mounting to a tractor having a fifth wheel, thereby providing a crane which may be temporarily mounted to the tractor for specific purposes and which may be readily removed to free the tractor for other purposes. Although a fixed-base type of crane has been shown in the present instance, it will be apparent to those skilled in the art that swivel or dipping cranes may also be mounted in essentially the manner described. Furthermore, although the preferred

embodiment of the present invention employs the king pin 18 for detachably connecting with the tractor fifth wheel 10, it will be apparent to the skilled technician that other clamping means may be readily employed to detachably secure the crane to the fifth wheel 10 without departing from the spirit of my invention, namely, to detachably mount a crane to the conventional tractor fifth wheel.

I claim:

1. A detachable crane adapted for quick and easy attachment to a tractor having a fifth wheel without altering the tractor construction and including a crane supporting frame comprising a pair of vertical uprights adjustably connected to a pair of vertical legs, a cross member secured to the base of said legs and adapted for attachment to a tractor frame, a horizontal winch supporting platform secured to the tractor fifth wheel and the said uprights, a pair of converging inclined crane booms connected to the forward portion of said winch platform and extending upwardly and rearwardly therefrom, being connected near their mid-portions with the said vertical uprights, a pair of upper boom supports extending from the upper ends of said booms to the upper ends of said uprights, and a pair of lower boom supports extending from the upper ends of said uprights to the forward portion of said winch supporting platform; a detachable king pin connected to the said winch supporting platform for detachably connecting with the tractor fifth wheel; detachable clamping means for clamping the said cross member of the crane supporting frame to the tractor frame; and a winch disposed on said winch supporting platform.

2. A detachable crane adapted for quick and easy attachment to a tractor having a fifth wheel without altering the tractor construction and including a crane supporting frame comprising a pair of vertical uprights adjustably connected to a pair of vertical legs, a cross member secured to the base of said legs and adapted for attachment to a tractor frame, a horizontal winch supporting platform secured to the tractor fifth wheel and the said uprights, a pair of converging inclined crane booms connected to the forward portion of said winch platform and extending upwardly and rearwardly therefrom, being connected near their mid-portions with the said vertical uprights, a pair of upper boom supports extending from the upper ends of said booms to the upper ends of said uprights, and a pair of lower boom supports extending from the upper ends of said uprights to the forward portion of said winch supporting platform; means for detachably mounting said winch supporting platform on said tractor fifth wheel; means for detachably clamping said cross member of the crane supporting frame to the tractor frame; and a winch disposed on said winch supporting platform.
